UNITED STATES PATENT OFFICE.

JOHN W. PIVER, OF CORDELE, GEORGIA.

INTERLOCKING FLOORING AND CEILING.

935,402.

Specification of Letters Patent. Patented Sept. 28, 1909.

Application filed June 30, 1908. Serial No. 441,084.

To all whom it may concern:

Be it known that I, JOHN W. PIVER, a citizen of the United States, residing at Cordele, in the county of Crisp and State 5 of Georgia, have invented certain new and useful Improvements in Interlocking Flooring and Ceiling; and I do hereby declare the following to be a full, clear, and exact description of the invention, such as will enable others skilled in the art to which it ap- 10 pertains to make and use the same.

My invention relates to improvements in interlocking flooring and ceiling, and the object of my invention is to provide tongued and grooved flooring and ceiling so made that the parts may be easily fitted together to form an absolutely tight joint at the top.

With this object in view, my invention consists in the construction and combinations of 20 parts as hereinafter described and claimed.

In the accompanying drawing—Figure 1 represents an end elevation partly in section, showing part of a floor made in accordance with my invention. Fig. 2 is a similar view 25 showing the method of putting the flooring together.

a represents a sub-floor or sill, and *b* strips of flooring. Each strip is provided with a tongue *c* on one side located prefer- 30 ably below the center thereof, and a groove *d* on the other side, arranged at about the same height, but slightly larger than the tongue *c*. The bottom of each strip *b* is beveled off, as shown at *e*. The strips are 35 secured in position by means of nails *f*, driven in diagonally in the usual way. The advantage of this construction is that after one strip has been nailed in position, the next strip may be easily fitted against it by 40 tilting it, as shown in Fig. 2, the beveled off portion *e* permitting such tilting movement, and then pushing the second piece snugly up against the first piece, as shown in Fig. 1.

This forms an absolutely tight joint at the top, as shown in Fig. 1. 45

While I have shown and described a beveled under lip in combination with a loose fitting tongue and groove, it is apparent that a beveled under lip is equally applicable and advantageous in combination with a 50 tight fitting tongue and groove.

Having thus described my invention, I claim:

1. A flooring or ceiling strip provided with the ordinary tongue and groove, but with the 55 lip under the groove made less in thickness than the distance between the tongue and the sill by beveling off the entire under side of the under lip of the groove, said beveled surface being wider than the tongue, sub- 60 stantially as described.

2. A floor or ceiling composed of strips each provided with the ordinary tongue and groove, but with the lip under the groove, as laid, made less in thickness than the distance 65 between the tongue and sill by beveling off the entire under side of the under lip of the groove, said beveled portion being wider than the tongue, substantially as described.

3. A floor or ceiling composed of strips 70 each provided with the ordinary tongue and groove, but with the groove deeper than the width of the tongue, and with the lip under the groove, as laid, made less in thickness than the distance between the tongue and sill 75 by beveling off the entire under side of the under lip of the groove, said beveled portion being wider than said tongue, substantially as described.

In testimony whereof, I affix my signature, 80 in presence of two witnesses.

JOHN W. PIVER.
